LOUIS W. SCHAAFF, OF WEEHAWKEN, NEW JERSEY

COIN-IN-THE-SLOT MACHINE FOR THE POLISHING OF FINGER NAILS

Application filed February 10, 1928. Serial No. 253,339.

This invention relates generally to a machine having a reciprocating element, and more specifically to an automatic machine for polishing and manicuring finger nails by means of a moving surface operative only upon the insertion of an authorized coin into the machine.

Proper care of the finger nails for reasons of health, sanitation and appearance is becoming more and more the concern of individuals. Up to the present time finger nails have, in the main, been treated by a manicurist or the individual himself, using hand implements. To resort to a manicuring establishment and have a skilled manicurist perform the treatment is both expensive and time-consuming. Not only is the actual treatment tedious, but additional loss of time frequently results at these establishments because available manicurists are already occupied with prior customers. For the individual to treat his finger nails with hand implements is also unsatisfactory. If he be a right handed person, for instance, he will find it difficult to properly manipulate the implements with his left hand to treat the finger nails on the right. He may be further handicapped by not having the proper implements at hand, at the time desired.

An object of the present invention is to provide mechanism for operating a treating element where the operation upon or treatment applied to the object treated consists of a series of to and fro reciprocations.

Another object of this invention is to provide a coin controlled reciprocating mechanism operative for a predetermined time upon the insertion of a coin.

Another object of this invention is to provide an automatic manicuring machine by means of which finger nails may be treated in a rapid and efficient manner.

Another object of this invention is to provide a nail polishing machine simple, practical and comparatively inexpensive to operate, designed for use in manicuring establishments and elsewhere, and capable of cleaning and polishing the nails of both hands without injury to the same.

Another object of this invention is to pro-

vide a nail polishing machine having a reciprocating nail treating surface, with means provided to feed a fresh supply of said surface into operative position as required.

Still another object of this invention is to provide a nail treating machine having a treating surface, properly enclosed and encased, access being obtained to the nail treating surface by inserting the authorized coin into the machine.

Another object of this invention is to provide a nail treating machine with a reciprocating treating surface properly enclosed and encased, reciprocation of the surface being obtained by inserting the authorized coin into the machine, the duration of the reciprocations and the operation of the machine being determined by a timing device.

A further object of this invention is to provide a coin control mechanism of special adaptability to applicant's particular nail treating machine.

A still further object of this invention is the provision of mechanism for measuring the number of reciprocations of the operating surface, means for throwing the prime mover out of operation after a predetermined number of reciprocations of the operating surface, and means for enclosing and locking the operating surface against unauthorized access.

A further object of this invention is to provide a coil control mechanism functioning to throw the prime mover into action and to unlock and open the shutter, so that operative access to the machine may be had.

A further object of this invention is to provide mechanism for carrying a band of treating material, with provision for feeding a section of the said band into operating position at each operation of the machine, so that a customer will be provided with a fresh and unused treating band for each coin insertion.

Another object of this invention is to provide a manicuring machine in which the polishing compound is carried by a reciprocating band and a fresh section of the band is fed into operative position for each customer in a sanitary manner.

A further object of this invention is to provide mechanism and means for opening the shutter, means for locking the shutter in open position until the period determined by the timing device has terminated, means for then unlocking the shutter from open position, means for moving it to closed position, and finally means for locking the shutter in closed position at the termination of the operating cycle.

Another object is to provide a nail manicuring coin controlled mechanism strong and durable, efficient and quiet in operation, and substantially "fool" proof.

Other objects of this invention will be in part obvious and in part pointed out as the disclosure proceeds.

In accordance with this invention, when a coin is dropped into the coin slot, it proceeds into a coin control mechanism and forms the connecting element between a pair of rotatable disks. When one of the disks is rotated manually by means of a handle, the second disk is rotated through a certain angle before the coin drops through the control mechanism and into a coin box. The disks are so spaced and formed that only coins of a definite size and shape will engage the second disk to rotate it and throw the machine into operation. The second disk above mentioned is connected to a switch device which is arranged to connect a small electric motor to a power source upon rotation of the disks. The motor drives a reciprocating buffer or polishing band adapted to move at considerable speed in a to and fro direction. Rotation of the second disk operates mechanism to unlock and open the shutter, so that access can be had to the reciprocating buffer to polish the finger nails. A timing device, having an arm engaging and following the reciprocating buffer, measures the number of reciprocations thereof, and after a predetermined number have been executed, throws the switch to shut off the motor, unlocks the shutter from its open position, and closes the same. The shutter then automatically locks in closed position. The machine is now in readiness to repeat the operation upon insertion of another coin. The polishing band is preferably carried on a spool or roll, and mechanism is provided for feeding a fresh section into polishing position across a padded frame adjacent the casing opening for each coin insertion, so that each customer will have his finger nails treated by a fresh and unused section of the band. The mechanism of the machine is compactly arranged and may be enclosed in an attractive casing to suit particular tastes and needs. The machine is not only adapted for installation in manicuring establishments and beauty parlors, but is particularly adapted for installation in waiting

rooms, subways, hotels and other places where people congregate.

In order that a clearer understanding of my invention may be had, attention is hereby directed to the accompanying drawings forming part of this application and illustrating certain possible embodiments of the invention.

Fig. 1 is a vertical side view of the machine with a side wall removed to show the interior operating mechanism of the machine, taken on line 1—1 of Fig. 4;

Fig. 2 is a vertical cross-sectional view of the machine showing side elevations of the reciprocating, coin control, and timing mechanisms in non-operative position, taken on line 2—2 of Fig. 4;

Fig. 3 is another vertical cross-sectional view of the machine showing the shutter in raised position with the reciprocating, coin control and timing mechanisms appearing in operating position, taken on line 3—3 of Fig. 4;

Fig. 4 is a horizontal cross-sectional view of the machine showing cross-sectional and top views of portions of the operating mechanism, taken on line 4—4 of Fig. 1;

Fig. 5 is another horizontal cross-sectional view of the machine, taken on line 5—5 of Fig. 1;

Fig. 6 is an enlarged side elevation of the coin control mechanism and the mechanism for feeding fresh sections of the polishing band into operative position;

Fig. 7 is another side elevation of the coin control mechanism with a coin inserted and about to throw the machine into operation, and the band feeding mechanism in operative engagement;

Fig. 8 is a detailed fragmental view of the band feeding mechanism, taken on line 8—8 of Fig. 6;

Fig. 9 is a side elevational view of the coin control mechanism showing a coin therein about to be ejected, the band feeding mechanism in operative engagement, and the device connected to the coin control mechanism throwing the switch controlling the motor;

Fig. 10 is a fragmental cross-sectional view of the coin control mechanism, taken on line 10—10 of Fig. 4;

Figs. 11 and 12 are side elevations of the coin engaging disks of the coin control mechanism;

Fig. 13 is a front elevation of the reciprocating band carrying frame showing a section of the band in operative position;

Fig. 14 is a front elevational view of the resilient cushion which supports a section of the band in operative position, the band being removed;

Fig. 15 is a cross-sectional view of the resilient band supporting cushion, taken on line 15—15 of Fig. 14;

Fig. 16 is an end elevation of the timing mechanism and the motor control switch, taken on line 16—16 of Fig. 5;

Fig. 17 is a fragmental horizontal cross-sectional view of the motor control switch, taken on line 17—17 of Fig. 2; and

Fig. 18 is another horizontal cross-sectional view of the motor control switch, taken on line 18—18 of Fig. 3.

10 Referring to the drawings, the polishing machine generally comprises a reciprocating band supporting structure 1, coin control mechanism 2, a timing device 3, an operating motor 4, and shutter control mechanism 5, all connected by various devices and cooperating together to form a unitary and efficient machine.

The entire mechanism is housed in a suitable casing, preferably, comprising a bottom plate 6, a removable top plate 7, a front wall 8, and a removable encasing member 9 constituting the two side and rear walls, all supported on a suitable pedestal 10.

20 The casing preferably has a vertical channel-shaped formation 11 (shown more particularly in Fig. 4) in the front wall 8 thereof, extending the full height of the casing, for a purpose hereafter to be described. An opening 12 is provided in the front wall, of such shape and size as to permit the free insertion of the fingers and finger nails to receive the polishing treatment. Horizontal top 13 and bottom 14 cross pieces, joining the ends of a pair of spaced vertical members 15 and 16 which are secured to the front wall 8 of the casing, serve to guide and direct the to and fro reciprocations of the band supporting structure. The band supporting structure comprises, broadly, a rectangular frame 17 guided in its reciprocations by means of a pair of pins 18 extending upwardly therefrom through suitable holes in top cross piece 13 and a pair of pins 19 extending downwardly therefrom through suitable holes in bottom cross piece 14. Coil springs 20 encircling each pin may be provided to facilitate the reciprocating operation and insure smoother running. A suitable tray 21 supported from the rectangular frame by means of brackets 22 is adapted to contain and hold a resilient cushion 23 adjacent to the opening 12. The cushion may be composed of rubber sponge, felt or other suitable cushioning material. A supply reel 24 carrying the band 25 is rotatably supported by spindle 26 journaled to side brackets 27 and 28 attached to the rectangular frame 17. Band 25 preferably consists of woven material impregnated with a polishing or abrasive powder, and is fed from supply reel 24 across the front face of cushion 23 over a feed cylinder 29, and finally wound upon reel 30 rotatably supported by spindle 31 journaled to bracket 27 and bracket 32 attached to the rectangular frame 17. Spindle 26 may

be withdrawn from its supporting brackets 27 and 28 by removing nut 33, thus permitting an exhausted supply reel to be removed and a freshly charged supply reel to be substituted. A leather gasket 34 or other suitable friction device may be disposed between the bracket 28 and supply reel 24, so that the reel does not rotate unless a slight pull is exerted on the band by feed cylinder 29, hereafter to be described. Spindle 31 supporting the take-up reel 30 may likewise be withdrawn from its supporting brackets 27 and 32 by removing a nut on the end thereof, thus permitting one reel to be removed and another substituted. The feed cylinder 29 is rotatably supported by shaft 35 journaled to bracket 27 and bracket 36 secured to the rectangular frame 17. A pulley wheel 37 secured to and rotating with shaft 35 and pulley wheel 38 secured to and rotating with spindle 31 are connected by suitable slip belting 39, so that take-up reel 30 is rotated each time feed cylinder 29 is rotated. Thus, it is seen that if the used band is not fed to the feed cylinder as fast as the band is wound thereon, the discrepancy is provided for and adjusted by slipping of the belt.

25 Suitable guide reels 40 and 41 journaled in the rectangular frame 17 may be used to guide the band to and from resilient cushion 23. As seen more particularly in Fig. 5, resilient cushion 23 is rectangular in horizontal cross-section with the sides thereof flared outwardly and conforming in shape to channel formation 11 in the front wall of the casing. Band 25 moves vertically across the cushion and is guided to conform to the front and flared side wall contour of the cushion member by guide fingers 42 secured to tray member 21, as clearly shown in Figs. 13 and 14. Thus, finger nail access may be had to the band covered front and side walls of the cushion, as shown in Fig. 5. It is understood, however, that a cushion of any desired horizontal cross-section can be used best adapted to facilitate the polishing or cleaning operation.

30 Rectangular frame 17 guided by cross pieces 13 and 14 and pins 18 and 19 is driven to reciprocate to and fro across the opening 12 by motor 4. The motor may be supported and removably held to the bottom plate 6 by means of a block 43 and screw bolts 44. A framework adapted to support portions of the operating mechanism is erected along the rear wall of the casing, and may consist of a pair of angle iron uprights 45 and 46 secured at their lower ends to bottom plate 6 and joined at their upper ends by angle iron 47. The motor 4 is operatively connected to the reciprocating frame 17 by means of suitable speed reduction devices; pulleys and belting, which are quiet running, being preferably used. To this end, I provide a pair of spaced apart, parallel supports 48 and 49

130

secured to framework upright 45 and the front wall 8 of the casing. A large pulley wheel 50 and small pulley wheel 51 are disposed between horizontal supports 48 and 49, and connected to shaft 52 journaled in journal blocks 53 and 54 secured to supports 48 and 49, respectively. Pulley wheel 55, fixed to the motor armature shaft 56, drives large pulley wheel 50 by means of an endless belt 57, rotating shaft 52 and small pulley wheel 51 fixed thereto. Another large pulley wheel 58 fixed to shaft 59 journaled in brackets 60 and 61 secured to bottom plate 6 is driven by small pulley wheel 51 through an endless belt 62. This series of pulley wheels and belting constitutes the speed reduction device, and is the preferred form, although it is understood that other reduction devices may be used within the contemplation of this invention.

A disk crank 63 is secured to the projecting end of shaft 59 and rotates therewith. The lower end of deformed connecting bar 64 is journaled to crank pin 65 of disk crank 63, and its upper end is pivotally secured to reciprocating frame 17 by means of a rod 66. Thus, it is seen that motor 4 reciprocates the frame 17 and a section of the band across opening 12 through the agency of pulleys, belting, disk crank and connecting bar, driving the same at a speed best suited for efficient polishing or other operation to be performed. The desired speed for a particular operation can be obtained by substituting different sets of pulley wheels.

The operation of the motor is controlled by the throw of a switch connecting or disconnecting the motor to the power source. Referring now particularly to Figs. 2, 9, 17 and 18, a conductor 67 leads, for instance, from the power source and connects with terminal 68 suitably secured to a non-conducting block 69 fastened to bottom plate 6. Conductor 70 leads from terminal 71, parallel with and spaced from terminal 68, and also secured to non-conducting block 69, to the motor. It is seen that if the proper conductor is inserted between the terminals 68 and 71, electric current will flow from the power source into the motor. A switch element 72 pivoted at 73 to plate 74 or other suitable support constitutes this terminal connector. Resistance to the throw of switch element 72 is provided for by means of a tongue 75 projecting laterally therefrom, the end of which is tapered. The tapered portion of the tongue 75 is adapted to frictionally slide over ridge 76 formed on the end of spring element 77 secured to plate 74, all clearly shown in Fig. 18. The terminals 68 and 71 are shown connected in Figs. 9 and 18 through the agency of switch element 72, and disconnected in Fig. 2. Switch element 72 carries a vertical extension 78 adapted to pivot outwardly on pin 79, but resiliently held in erect position by means

of a leaf spring 80 secured to switch element 72 for a purpose hereafter to be described.

Switch element 72, to connect the motor to the power source, is adapted to be thrown by a coin control mechanism now to be described. The coin control mechanism generally comprises a disk member 81 fixed to shaft 82 supported by and journaled to brackets 83 and 84. Shaft supporting brackets 83 and 84 are secured to a horizontal plate member 85 supported firmly in position by post 86 secured to horizontal frame member 47. A second disk member 87 journaled on shaft 82 has its inside face spaced from and parallel with the inside face of the first-mentioned disk 81. The space between the disks is in line with the coin slot 88 in top member 7 and coin slot 89 in plate 85, so that the coin, which the coin control mechanism is designed to receive, will readily drop between the disks. The inside face of disk 81 appears as shown in Fig. 11. The coin, when deposited between the disks, rests on hub portion 90 of disk 81. Disk 81 also has an elongated aperture 91 in its side wall. One end of the aperture terminates in an enlarged opening 92, of such dimension that the proper coin inserted in the machine can be removed through this enlarged opening. Disk 81 is further provided with a thickened edge portion 93 substantially closing the space between the disks, the thickened edge having a rounded abutment portion 94 for a purpose hereafter to be described.

Disk 87 carries a pair of inwardly projecting lugs 95 and 96, against which the edge of the inserted coin is adapted to seat. A grooved track 97 is also formed on the inside face of disk 87, for a purpose presently to be described. Disk 87 may be rotated manually and externally of the casing by means of handle 98 secured thereto and projecting through slots in plate 85 and top member 7.

The proper coin is dropped between the disks before rotating either disk. Disk 81 is then positioned as shown in Fig. 6, with the enlarged opening 92 vertically beneath the coin slot 88. The coin is prevented from falling out of this enlarged opening when the disk is in this position, by the spring blade 99, whose outer end 100 presses against the side of the coin and holds it within the opening 92. Spring plate 99 may be fixed in position to plate 85 by screws 101 or other suitable means. As disk 87 is rotated by a lateral pull on handle 98, lugs 95 and 96 engage the edge of the coin and move it forward, illustrated in Fig. 7. The forward top edge of the coin is thus moved into contact with rounded abutment 94 of the thickened edge portion. Further rotation of disk 87 will cause disk 81 to rotate, as is readily seen from Fig. 9.

A pick member 102 secured in a suitable

manner to plate 85 has an upturned coin removing point 103, adapted to slide in grooved track 97 heretofore described. As rotation of disk 87 and disk 81 is continued, the pick point 103 slides under the inner side of the coin, as shown in Fig. 9, and gradually wedges the coin out of engagement with lugs 95 and 96 and rounded abutment 94, finally throwing the coin out of the enlarged opening 92 into coin box 104. Coil spring 105 connected to horizontal frame member 47 and pin 106 projecting from the disk 87 returns the disk to neutral position when the handle is released. Coil spring 107 secured to pin 108 projecting from disk 81 and to post 86 pulls the disk back into neutral position as soon as the coin has been ejected.

Bell crank lever 109 journaled to pin 110 supported by plate 74 is operatively connected for rocking movement to disk 81 through connecting rod 111. As shown in Fig. 2, arm 112 of bell crank lever 109 is adapted to engage switch element extension 78 to throw the switch and start the motor.

A timing device is provided to stop the motor after the band carrying frame 17 has made the predetermined number of reciprocations. A pair of spaced apart upright plates 74 and 113, secured together to bottom plate 6 in a suitable manner, and secured to each other by posts 114, constitute the supporting framework for the timing mechanism. A deformed arm 115 journaled at one end to shaft 116 secured to plates 74 and 113 has a pan formation 117 at its other end extending under and adapted to engage the lower end of one of the downwardly extending pins 19. A pad 118 formed of rubber or other resilient material may be seated on pan formation 117. The pad is continually held in abutting contact with the lower end of pin 19 by means of a coil spring 119 connected to arm 115 and one of the posts 114 joining plates 74 and 113, as shown in Fig. 3. A ratchet wheel 120, connected to shaft 116, is adapted to be rotated by a pawl member 121 pivoted at 115' at its lower end to the deformed arm 115. The pawl 121 is held in operative engagement with the teeth of the ratchet wheel 120 by means of a coil spring 122 attached to a pin 123 projecting from the pawl and a pin 124 projecting from the deformed arm. Downward movement of the arm produced by downward movement of frame 17 causes pawl member 121 to engage a tooth of the ratchet wheel, to rotate the wheel through a certain fixed angle. Upward movement of the arm, permitted by upward movement of the frame, causes the pawl member to disengage from the aforementioned tooth and move to the next tooth on the ratchet wheel.

It is understood that the relationship between the arm 115 and ratchet wheel teeth is such that pawl 121 engages successive teeth on the ratchet wheel with each successive

downward movement of the arm. Thus, each complete reciprocation of the frame rotates the ratchet wheel through an angle measured by the pitch of the ratchet teeth.

Reduction gearing, as shown in Figs. 5 and 15, comprises small gear 125 secured to shaft 116 and rotated by ratchet wheel 120, and rotating large gear 126 fixed to shaft 127 journaled to the side plates 74 and 113. One end of shaft 127 projects through plate 74 and has a disk 128 fixed to the end thereof. A stud member 129 is secured to the disk near its edge and is adapted to engage switch element extension 78 to throw the switch and stop the motor as the disk is rotated through the reduction gearing by ratchet wheel 120. Thus, it is seen that the switch is thrown and the motor stopped at each complete revolution of the disk 128, measured by a certain definite number of reciprocations of frame 17. The number of reciprocations of frame 17 required to move disk 128 through a complete revolution is determined by the relative size of the reducing gears used and the diameter of ratchet wheel 120. It is understood that by using the proper set of reduction gears, the motor can be stopped at the end of any desired number of frame reciprocations. A friction brake, comprising a supporting element 130 and a friction pad 131 secured thereto, may be used to frictionally engage a side face of ratchet wheel 120 to prevent rotation thereof except as rotated by pawl member 121.

Before the switch can be thrown to start the motor, switch element extension 78 must be removed from the path of pin 129, as is readily seen in Fig. 16. This is accomplished in the following manner. Arm 112 of the rocking lever has a tapered projecting nose 132 formed on its end, clearly shown in Fig. 17. When the bell crank lever is rocked through the rotation of coin actuated disk 81, tapered nose 132 at the end of arm 112 engages switch element extension 78, and pivots it outwardly against the action of leaf spring 80 as it slides off the tapered nose 132, until it finally clears pin 129. Switch element extension 78 ceases to pivot outwardly when it strikes the squared portion 133 at the end of arm 112. The extension is then moved forwardly by arm 112 against the action of latch spring 77, until the terminals 68 and 71 are electrically connected by switch element 72. The amount of throw of switch element 72 can be fixed by stop pins 134, as shown in Fig. 2.

Shutter member 135 is normally in closed and locked position, and is only unlocked and opened by the rotation of disk 81, rotatable only when the proper coin has been inserted. Referring to Fig. 2, a bell crank lever pivoted to bracket 136 secured to top cross piece 13 has one arm 137 connected to

the shutter 135 by means of a connecting link 138 pivotally connected to the shutter by means of a lug element 139. The other arm 140 of the bell crank lever is connected to one end of a locking arm 141. An upper notch 142 and a lower notch 143 are cut in the other end of locking arm 141 with which upwardly projecting lug 144 is adapted to cooperate. Lug 144 may be formed as an integral part of its inclined support 145 secured to a horizontal angle bar 146 extending between uprights 45 and 46. When lug 144 is in engagement with the upper notch 142, shutter 135 is locked in open position, as shown in Fig. 3. When lug 144 is in engagement with lower notch 143, shutter 135 is locked in closed position, as shown in Fig. 2. Coil spring 147 secured to prong 148 projecting from the end of locking bar 141 and to lug support 145 holds the notched end of the locking bar against lug 144 and prevents jarring disengagement of the lug and notch.

Coin controlled means, however, are provided for lifting bar 141 out of locking engagement with lug 144. A cam block 149 of proper contour is secured to disk 81. Lever 150 secured to rod 151 journaled at its ends to uprights 45 and 46 is adapted to ride over cam block when disk 81 is rotated. A lifting lever 152 fixed to rod 151 and rotatable therewith has a shoe formation 153 at its outer end projecting laterally therefrom. Shoe 153 is adapted to ride over incline surface 154 formed on the underside of bar 141. Now it is seen that as coin engaged disk 81 is rotated, cam block 149 swings the upper end of lever 150 in an outward direction against coil spring 155, rotating rod 151 through a small angle, raising shoe end 153 of lever 152, which in turn raises the lower end of locking bar 141 against the action of coil spring 147 and out of locking engagement with lug 144.

While bar 141 is held in raised unlocked position by lever 152, shutter 135 is opened by the exertion of a longitudinal rearward pull on bar 141. This is accomplished by crank arm 156 secured to the end of shaft 82 and rotating with coin engaged disk 81. A stud element 157 projecting laterally from the lower end of crank arm 156 extends through an elongated slot 158 in locking bar 141. As coin engaged disk 81 is rotated, said element 157 engages the bar 141 and carries it rearwardly, until shutter 135 is raised and lug 144 slides into engagement with upper notch 142, due to the pull exerted by coil spring 147. At this point the coin is ejected from the coin control mechanism, and coin engaged disk 81 is pulled back to normal position by coil spring 107.

Means are provided for unlocking shutter 135 from its open position, closing it, and locking it in closed position. As illustrated

in Fig. 2, a connecting rod 159 joins switch element extension 78 to a lever 160 fixed to a rod 161 journaled in a suitable bracket 162. Lever 163 is fixed to rotate with rod 161 and is connected to a lever 164 by means of a connecting rod 165. Lever 164 is fixed to a rod 166 journaled in a bracket 167 secured to lug support 145. Thus, by means of a series of levers and connecting rods, rod 166 is rotated through a small angle each time switch element 72 is thrown. Rod 166 is rotated in a counter-clockwise direction by bell crank lever 109 connected to coin engaged disk 81 and clockwise by stud member 129 carried by disk 128 rotated by the timing mechanism. Rod 166 has secured thereto a small trip plate 168 adapted to engage the lower corner 169 of the locking bar 141 to raise the bar out of locking engagement with lug 144 as the rod is rotated counter-clockwise by coin engaged disk 81, as above described. The raising movement is rapid; after which trip plate 168 gives the locking bar a forward throw, which, with the aid of gravity, moves the shutter to closed position. The downward pull exerted by coil spring 147 on bar 141 causes lug 144 to slip into lower notch 143 to lock the shutter when it has reached its closed position. When stud member 129 on disk 128 carries switch element extension 78 forwardly, stopping the motor, trip plate 168 is returned to normal inoperative position, permitting the lower corner 169 of the locking bar to be moved thereover, as the shutter is opened. Thus, it is seen that the shutter is automatically unlocked and opened by coin control mechanism, and automatically unlocked from open position, moved to closed position, and locked in closed position by timing mechanism.

Means are also provided to move a fresh section of the band material into operative position across the cushion during the engagement of lever 98 with disk 81 and accomplished during the first few reciprocations of the band supporting frame. Referring to Figs. 6, 7 and 8, a ratchet wheel 170 is fixed to and rotatable with feeding cylinder 29, heretofore described. A pawl member 171 is fixed to shaft 172 journaled to horizontal supporting members 48 and 49. The pawl is normally held out of operative engagement with the teeth of the ratchet wheel by coil spring 173 secured to the supporting member 49 and downwardly extending lever 174 fixed to shaft 172. A lever 175 fixed to shaft 172 is joined by connecting a rod 176 to another lever 177 fixed to rod 151. A leaf spring 178 fixed to lever 175 is arranged to exert a pressing force on the head of pawl member 171, pressing it toward the ratchet teeth and against the action of coil spring 173. When the coin engaged disk is rotated as above described, levers 177 and 175 are swung outwardly, increasing the pressure of leaf

spring 178 on the head of pawl member 171 until the pawl member is moved into operative engagement with the ratchet wheel. At the same time, and by the same rotation of the coin engaged disk, bell crank lever 107 throws the motor into action, reciprocating band supporting frame 17. Feeding cylinder 29 and ratchet wheel 170, carried by the frame, now move upwardly and downwardly. As pawl member 171 is at this moment in operative engagement with the ratchet wheel teeth, the ratchet wheel and feeding cylinder are rotated through a certain angle at each upward movement of the frame. This rotation, it is seen, continues as long as the pawl member engages the ratchet wheel. But since the pawl member is thrown into ratchet engagement by rotation of the cam engaged disk, this engagement only continues while the coin is rotating disk 81. As soon as the coin is ejected, disk 81 is returned to its normal position by coil spring 107. Thus, it is seen that pawl 171 engages ratchet wheel only momentarily, but sufficiently long to engage at least one tooth and rotate the ratchet wheel through the arc of that tooth, for a purpose presently to be described.

Ratchet wheel 170 has two teeth, 179 and 180, spaced diametrically apart, of greater pitch than other teeth of the wheel, as shown in Figs. 6 and 7. The head of an elongated pawl member 181 pivoting about pin 182 secured to frame support 49 is forced to ride on the ratchet wheel teeth by coil spring 183. Teeth 179 and 180 are of such length that the elongated pawl merely idles on them when the band supporting frame is reciprocated. Now, when a coin has been inserted into the machine and coin engaged disk 81 is rotated, pawl 171 is moved into operative engagement with the ratchet wheel 170 and rotates the wheel through an arc measured by the pitch of the engaged tooth. This initial rotation of the wheel is sufficient to move the head of elongated pawl 181 off the large tooth, and upon further reciprocation of the frame regularly engages successive smaller teeth. The coin by this time has been ejected, coin engaged disk 81 returned to neutral position, and pawl 171 moved out of operative engagement with the ratchet wheel. Elongated pawl 181 continues to engage the smaller teeth rotating the wheel and feeding cylinder 29, until the next large tooth is reached. The pawl is then no longer able to rotate the wheel and feeding cylinder and idles on the large tooth. Thus, it is seen that, by means of the initial rotation of the ratchet wheel effected by pawl 171 and the later rotation effected by pawl 181, the feeding cylinder is rotated through a 180° angle during the initial reciprocations of the band supporting frame. The surface of the feeding cylinder may be covered with a series of minute needles or other devices adapted to

engage the band and pull it over the resilient cushion as the cylinder is rotated. Thus, it is seen that a fresh and unused section of the band is moved into operative position during the initial period of operation of the machine.

The operation of the machine may be described as follows. To start the machine, a coin of the authorized kind is dropped into coin slot 88, and lodges between the disks 81 and 87. Handle 98 is then grasped and pulled forwardly, during which movement lugs 95 and 96 on disk 87 engage the edge of the coin and move it forwardly, the upper front edge of the coin striking the rounded abutment 94 formed on coin engaged disk 81. Disk 81 then rotates along with disk 87. As coin engaged disk 81 begins to rotate, cam plate 149 secured thereto swings lever 150 outwardly, turning rod 151, raising the shoe end 153 of lever 152, which in turn raises lower notch 143 on the locking arm 141 out of engagement with lug 144. The shutter is now unlocked. Upon further rotation of the coin engaged disk 81, crank arm 156 connected thereto engages the locking bar 141 and exerts a longitudinal pull thereon, carrying it rearwardly, raising the shutter 135. When the shutter has been moved to full open position, lug 144 slips into upper notch 142, due to the downward pull of coil spring 147, and the shutter is locked in open position.

Bell crank lever 109 is moved into engagement with switch element extension 78, and swings it outwardly to avoid stud 129. The switch element extension is then carried along with the bell crank lever as coin engaged disk 81 is rotated, until switch element 72 is thrown, electrically connecting terminals 68 and 71 and starting the motor. After this has transpired, and during the final stage of rotation of disk 81, pick point 103 slides under the coin, loosens it from its clamped lodging between lugs 95 and 96 and abutment 94, and finally ejects it through enlarged opening 92. Disk 81 is then pulled back to neutral position by coil spring 107, also carrying bell crank lever 109 back to neutral position. The coin has done its work.

When lever 150 is swung outwardly by the rotation of disk 81, pawl 171 is moved into operative engagement with ratchet wheel 170. As soon as the switch element is thrown and the motor started, band carrying frame 17 begins to move up and down in a reciprocating manner. Pawl 171 engages a tooth of the ratchet wheel, turning the wheel through a small arc measured by the pitch of the tooth, sufficient to move elongated pawl 181 from its idling position on one of the large teeth of the wheel. When this is accomplished, pawl 171 has served its purpose and disengages from the ratchet wheel teeth as soon as disk 81 returns to neutral position upon ejection of the

coin. Feeding cylinder 29 is revolved until the next large tooth is reached by elongated pawl 181. Using two large teeth as shown in the drawings, the feeding cylinder, which engages the polishing band, will be revolved 180°, a sufficient distance to draw the required length of fresh band from reel 24 across the cushion 123 into polishing position. The length of section drawn from reel 24 is, of course, determined by the diameter of the feeding cylinder 29 and the number of large teeth on ratchet wheel 170. The finger nails may then be held against the reciprocating polishing band, cleaing and polishing them.

5 Arm 115 follows the reciprocating frame 17, and the pawl 121 thereto attached rotates ratchet wheel 120 through an arc measured by the pitch of its teeth, at each downward movement of the frame. Disk 28 is connected 10 to the ratchet wheel 120 by gearing. Stud member 129 engages and throws switch element extension 78, stopping the motor. Disk 128 has then made a complete revolution.

15 Trip plate 168, joined to switch element extension 78 through a series of levers and connecting rods, is also operated by the same movement, raising locking bar 141 out of engagement with lug 144 and throwing it forwardly to close the shutter. Lug 144 then 20 slips into lower notch 143, locking the shutter in closed position, completing the cycle of operation. The shutter is of light weight and drops gently, so that the fingers being polished cannot be injured by the dropping shutter.

25

30 The polishing band, as well as the polishing compound, are of such texture and characteristics that the compound will readily adhere to the band and be carried along therewith during the reciprocations of the band. By this novel arrangement the compound can be applied to the finger-nails and the nails polished simultaneously and by the same device. Furthermore, since the band is completely enclosed within the casing when not in use, and a fresh and unused section is moved into position at each operation of the machine, the 35 polishing operation is clean, sanitary and hygienic.

40 While applicant's machine is particularly adapted for polishing finger-nails, it is understood that operations such as sanding, grinding, brazing, sawing or other operation or treatment requiring a reciprocating medium, may be performed thereon, by simply securing to the reciprocative frame of the machine the proper operative band or element. Therefore, as many changes could be made in the above construction, and as many apparently widely different embodiments of this invention could be made without departing from the scope thereof, it is intended that 45 all matter contained in the above description

or shown in the accompanying drawings shall be interpreted as illustrative and not in a limiting sense.

What I claim is:

5 1. In an apparatus of the character described, the combination with an operating surface, means for reciprocating said surface, coin control mechanism for throwing said reciprocating means into operation and control means for throwing said reciprocating means out of operation after a predetermined number of reciprocations of said surface.

10 2. In an apparatus of the character described, the combination with an operating surface, a casing, an opening in said casing, means for reciprocating said surface across said opening, a shutter for said opening normally in closed position, coin control means for opening said shutter and throwing said reciprocating means into operation, and means for throwing the reciprocating means out of operation.

15 3. In a machine of the character described, the combination with an operating surface, an opening, means for reciprocating said surface across said opening, a shutter for said opening, coin control means operative to simultaneously open said shutter and throw said reciprocating means into operation, and means for throwing the reciprocating means out of operation.

20 4. In an apparatus of the character described, the combination with an operating surface, an opening, means for reciprocating said surface across said opening, a shutter for said opening, coin control mechanism operative to simultaneously open said shutter and throw said reciprocating means into operation, means operative to close said shutter after a predetermined number of reciprocations of said surface across the opening, and means for throwing the reciprocating means out of operation.

25 5. In an apparatus of the character described, the combination with an operating surface, an opening, means for reciprocating said surface across said opening, a shutter for said opening normally in closed position, means operative to open said shutter, and to simultaneously throw said reciprocating means into operation, means operative to close said shutter after a predetermined number of reciprocations of said surface across said opening, and means for throwing the reciprocating means out of operation.

30 6. In an apparatus of the character described, the combination with an operating surface, an opening, means for reciprocating said surface across said opening, a shutter for said opening, coin control means operative to open said shutter and means for holding said shutter in locked open position during the continuance of said reciprocations.

7. In an apparatus of the character described, the combination with an operating surface, an opening, means for reciprocating said surface across said opening, a shutter for said opening, coin control means operative to open said shutter and mechanism including means operative to unlock and means operative to close said shutter after a predetermined number of reciprocations of said surface across the opening. 70
8. In an apparatus of the character described, the combination with an operating surface, an opening, means for reciprocating said surface across said opening, a shutter for said opening, coin control means operative to open said shutter, and mechanism including means operative to close said shutter and means operative to lock said shutter in closed position after a predetermined number of reciprocations of said surface across said opening. 80
9. In a polishing machine of the character described, the combination with a polishing surface, means for reciprocating said surface, 85 coin control means for throwing said reciprocating means into operation, and means for throwing the reciprocating means out of operation. 90
10. In a polishing machine, the combination with a polishing surface, an opening, means operative to reciprocate said surface across said opening, a shutter for said opening, mechanism simultaneously operative upon the insertion of a coin into said machine to open said shutter and to throw said reciprocating means into operation, and means for throwing the reciprocating means out of operation. 95
11. In combination with a receptacle having an opening, a shutter for said opening, and coin control means for automatically operating said shutter comprising a pair of spaced rotatable disks adapted to receive a coin therebetween, means associated with said disks adapted to engage the coin and rotate said second disk upon rotation of the first, an aperture in the wall of one of said disks, means to remove the coin through said aperture after said disks have been rotated through a predetermined angle, and means connecting said second disk with said shutter. 105
12. Coin control mechanism comprising, in combination, a pair of spaced rotatable disks adapted to receive a coin therebetween, a laterally projecting lug on each of said disks adapted to engage the edges of the coin to rotate said second disk upon rotation of the first, an aperture in the wall of one of said disks, a resilient member adapted to releasably retain the coin within said aperture, and means to remove the coin through said aperture after rotation of said disks through a predetermined angle. 110
13. Coin control mechanism comprising, in combination, a pair of spaced rotatable disks adapted to receive a coin therebetween, an inwardly projecting lug on each of said disks adapted to engage the edges of the coin and rotate said second disk upon rotation of the first, an elongated aperture in the wall of one of said disks having an enlarged opening at one end, a resilient member adapted to releasably retain the coin within said enlarged opening during the beginning of the rotation movement, and means adapted to remove the coin through said enlarged opening after rotation of said disks through a predetermined angle. 120
14. Coin control mechanism comprising, in combination, a pair of spaced rotatable disks adapted to receive a coin therebetween, an inwardly projecting hub on one of said disks on which the coin is adapted to rest, an inwardly projecting lug on each of said disks adapted to engage the edges of the coin and rotate said second disk upon rotation of the first, an elongated aperture in the wall of one of said disks having an enlarged opening at one end, a resilient member adapted to releasably retain the coin within said enlarged opening during the beginning of the rotation movement, and a pick member projecting into said elongated aperture and adapted to remove the coin through said enlarged opening after rotation of said disks through a predetermined angle. 125
15. In a polishing machine, the combination with a polishing surface, an electric motor operatively connected to reciprocate said surface, and coin controlled switch mechanism for starting said motor including a pair of spaced rotatable disks adapted to receive a coin therebetween, means associated with said disks adapted to engage the coin to rotate said second disk upon rotation of the first, a switch electrically connected to said motor, and means connected to said second disk and adapted to engage said switch to throw the same after said disks have been rotated through a predetermined angle. 130
16. A coil controlled switch mechanism for starting an electric motor comprising, in combination, a pair of spaced rotatable disks adapted to receive a coin therebetween, means associated with said disks adapted to engage the coin to rotate said second disk upon rotation of the first, a switch adapted for electrical connection with said motor, and a pivoted bell crank lever having one arm connected to said second disk and its other arm adapted to engage said switch to throw the same after said disks have been rotated through a predetermined angle. 135
17. In a machine of the character described including, in combination, a casing, an opening in said casing, a shutter for said opening normally in locked position, a locking bar connected to said shutter, a notch in said

- locking bar, a lug adapted to cooperate with said notch, and coin control mechanism operative to raise said bar out of locking engagement with said lug to unlock the shutter upon the insertion of an authorized coin in said machine.
18. In a machine of the character described including, in combination, a casing, an opening in said casing, a shutter for said opening normally in locked position, and coin control mechanism operative to unlock said shutter including a pair of spaced rotatable disks, means associated with said disks whereby upon the insertion of an authorized coin between said disks and the rotation of one of said disks, the second disk is rotated, a locking bar connected to said shutter, a lug adapted to engage said locking bar, and means operative to engage said second disk to raise said bar out of locking engagement with said lug when said second disk is rotated.
19. In a machine of the character described including, in combination, a casing, an opening in said casing, a shutter for said opening normally in locked position, a bell crank lever hinged to said shutter, a locking bar connected to said lever, a lug adapted to engage said locking bar, and coin control means operative to move said bar out of locking engagement with said lug to unlock said shutter upon the insertion of an authorized coin into said machine.
20. In a machine of the character described including, in combination, a casing, an opening in said casing, a shutter for said opening normally in closed and locked position, a locking bar connected to said shutter, a lug adapted to engage said locking bar, and coin control mechanism operative to move said bar out of engagement with said lug to unlock said shutter, and then to open said shutter.
21. In a machine of the character described including, in combination, a casing, an opening in said casing, a shutter for said opening normally in closed and locked position, a bell crank lever hinged to said shutter, a locking bar connected to said lever, a lug adapted to engage said locking bar, and coin control mechanism operative to raise said bar out of engagement with said lug to unlock said shutter and then to carry said bar in a longitudinal direction to move said shutter to open position.
22. In a machine of the character described including, in combination, a casing, an opening in said casing, a shutter for said opening normally in closed and locked position, and mechanism operative to unlock and open said shutter including a pair of spaced rotatable disks, means associated with said disks whereby upon the insertion of an authorized coin between said disks and the rotation of one of said disks, the other of said disks is rotated, a locking bar connected to said shutter, a lug adapted to engage said locking bar, means operative to raise said locking bar out of engagement with said lug to unlock said shutter upon initial rotation of said second disk, and means operative to move said bar longitudinally to open said shutter upon further rotation of said second disk.
23. In a machine of the character described including, in combination, a casing, an opening in said casing, a shutter for said opening normally in closed position, and mechanism operative to open said shutter including a pair of spaced rotatable disks, means associated with said disks whereby upon the insertion of an authorized coin between said disks and the rotation of one of said disks, the other disk is rotated, a locking bar connected to said shutter, a slot in said bar, and a lever connected to said second disk and adapted to engage said slot to move said bar longitudinally to open said shutter.
24. In a machine of the character described including, in combination, a casing, an opening in said casing, a shutter for said opening normally in closed and locked position, and coin control mechanism operative to unlock and open said shutter including a rotatable disk, a locking bar connected to said shutter, a lug adapted to engage said locking bar, a cam surface connected to said disk, means operative to engage said cam surface to raise said bar out of engagement with said lug to unlock the shutter, and a lever connected to said disk and adapted to move said bar longitudinally to open said shutter upon further rotation of said disk.
25. A polishing machine of the character described comprising, in combination, a casing, an opening in said casing, a shutter for said opening, a polishing surface adjacent said opening, means operative to reciprocate said surface, coin control means for throwing said reciprocating means into operation, automatic means associated with said coin control means for opening said shutter when said surface begins to reciprocate, and automatic means operative to close said shutter at the end of a predetermined number of reciprocations.
26. A polishing machine of the character described comprising, in combination, a casing, an opening in said casing, a shutter for said opening, a polishing surface adjacent said opening, means operative to reciprocate said surface, coin control means for throwing said reciprocating means into operation, automatic means associated with said control means operative to open said shutter when said surface begins to reciprocate, means operative to hold said shutter open during a predetermined number of said reciprocations, and automatic means operative to close said shutter at the end of said predetermined number of reciprocations.
27. A polishing means of the character de-

scribed comprising, in combination, a casing, an opening in said casing, a shutter for said opening, a polishing surface adjacent said opening, means operative to reciprocate said surface, coin control means for throwing said reciprocating means into operation, automatic means associated with said control means, operative to open said shutter when said surface begins to reciprocate, and means operative to hold said shutter open during the continuancy of said reciprocations.

28. A polishing machine of the character described comprising, in combination, a casing, an opening in said casing, a shutter for said opening, a polishing surface adjacent said opening, means operative to reciprocate said surface during periods of a predetermined number of times, coin control means for throwing said reciprocating means into operation, means operative to lock said shutter in open position during the continuancy of said reciprocating periods, and automatic means operative to unlock said shutter from its open position at the end of said periods of reciprocation.

29. A polishing machine of the character described comprising, in combination, a casing, an opening in said casing, a shutter for said opening, a polishing surface adjacent said opening, means operative to reciprocate said surface, coin control means for throwing said reciprocating means into operation, means operative to lock said shutter in open position during the continuancy of said reciprocations, and mechanism having means adapted to engage said surface as it reciprocates, and means to disengage said locking means from locking position to permit said shutter to close after a predetermined number of reciprocations of said surface.

30. A polishing machine of the character described comprising, in combination, a casing, an opening in said casing, a shutter for said opening, a polishing surface adjacent said opening, means operative to reciprocate said surface, coin control means for throwing said reciprocating means into operation, means comprising a locking bar connected to said shutter and a lug adapted to engage said bar to lock said shutter in open position during the continuancy of said reciprocations, and mechanism including means adapted to engage said surface as it reciprocates and means to disengage said bar from said lug to permit said shutter to close after a predetermined number of reciprocations of said surface.

31. A polishing machine of the character described comprising, in combination, a casing, an opening in said casing, a shutter for said opening, a polishing surface adjacent said opening, means operative to reciprocate said surface, coin control means for throwing said reciprocating means into operation, a locking bar connected to said shutter, a lug

adapted to engage said bar to lock said shutter in open position during the continuancy of said reciprocations, and mechanism including a trip device operative to raise said bar out of locking engagement 70 with said lug to permit said shutter to close after a predetermined number of reciprocations of said surface.

32. In a machine for polishing finger nails, the combination with a polishing surface, 75 a casing having an opening, means for reciprocating said surface opposite said opening, coin control means for throwing said reciprocating means into operation, means for feeding a fresh supply of said surface 80 into operative position at predetermined times, and means for throwing the reciprocating means out of operation.

33. In a machine for polishing finger nails, the combination with a polishing surface 85 comprising a band impregnated with polishing material, a casing having an opening, means for reciprocating said band opposite said opening, coin control means for throwing said reciprocating means into operation, 90 and means for throwing the reciprocating means out of operation.

34. In a machine for polishing finger nails, the combination with a polishing surface comprising a band impregnated with polishing material, a casing having an opening 95 means for reciprocating said band opposite said opening, coin control means for throwing said reciprocating means into operation, means for moving a predetermined section 100 of fresh band material into operative position at predetermined times, and means for throwing the reciprocating means out of operation.

35. In a nail polishing machine, in combination, a roll of band material impregnated with nail polish, a casing having an opening and coin controlled means for drawing a length of said ribbon from said roll and placing said length in operative position opposite said opening at predetermined 110 times.

This specification signed this 6th day of February, 1928.

LOUIS W. SCHAAFF.
